UNITED STATES PATENT OFFICE.

SAMUEL M. GREEN, OF CLEVELAND, OHIO.

RECEIPT AND RECEIPT-BOOK AND HOLDER.

1,364,499.

Specification of Letters Patent.

Patented Jan. 4, 1921.

Application filed February 24, 1920. Serial No. 360,372.

To all whom it may concern:

Be it known that I, SAMUEL M. GREEN, a citizen of the United States, residing at Cleveland, in the county of Cuyahoga and State of Ohio, have invented certain new and useful Improvements in Receipts and Receipt-Books and Holders, of which the following is a specification.

It is well known that considerable difficulty arises in the making of collections, especially where rental or installment payments are made, in keeping accurate records of amounts received, and preventing attempts on the part of unscrupulous persons from trying to defraud collectors by raising receipts somewhat after the manner of raising checks.

With the above in view, the primary object of this invention has been to produce a safety or protective receipt especially adapted for making collections of the character mentioned, but useful in many other ways where receipts are quite commonly employed.

An additional object of the invention has been to produce a receipt book or holder conveniently combining with a cover, the pad of receipts, a carbon sheet retainer adapted to be readily inserted between the original and duplicate receipt, a calendar, a pocket to receive the duplicate checks retained by the collector, a pencil holder, and possibly other minor devices useful in a receipt book or holder of this kind.

For a full understanding of the invention reference is to be had to the annexed drawings, and the following detail description. In the drawings the figures are as follows:

Figure 1 is a perspective view of a receipt book embodying the invention, the carbon sheet retainer being shown in operative position over a duplicate receipt, and the original receipt being upraised and broken away.

Fig. 2 is a longitudinal section view through the book or holder in open condition.

Figs. 3 and 4 are plan views of receipts such as used for the purposes of the invention, the former for general use and the latter for rental use particularly.

Figs. 5 and 6 are similar views, showing respectively the duplicate receipts to be used in connection with those of Figs. 3 and 4.

Fig. 7 is a perspective view of the hook plate to which the carbon sheet retainer is attached.

Fig. 8 is a sectional view through the car-

bon sheet retainer, showing the manner in which the free ends of the holder are held together by the clip.

Fig. 9 is a section about on the line 9—9 of Fig. 1.

In the following description and in the drawings similar reference characters refer to similar parts.

My receipt book or holder comprises the front cover member 1 and the back cover member 2, which are made of stiff or flexible construction according to how expensive it is desired to make the article, which of course will be finished nicely and supplied to the trade in different styles.

On the inside of the cover member 1 is the pocket 3 for the duplicate receipts, the same being connected to the cover member 1 by the bellows folds 4 of common form. The pad of receipts is arranged on the cover member 2, and is designated generally at 5. The pad is provided at one end with a tab 5^a which fits in a pocket on the outer end of cover member 2, thus holding the pad in place in a removable manner. The receipts are in pairs constituting originals and duplicates. The original receipts may be of the forms shown in Figs. 3 and 4, and the duplicate receipts will preferably be of the forms shown in Figs. 5 and 6. The duplicate receipts bear a space where remarks may be written thereon, and they also have a space for the account number, in the case of the general receipt of Fig. 3. In the case of the rental receipt duplicate of Fig. 6, the building or house number may be indicated in a suitable space provided therefor.

A pencil may be held in place on the lower edge of the cover member 2 by loops 9.

A calendar is held in place in any suitable manner on the outer face of the pocket 3, and is designated at 10.

Hooks 6 extend from a plate 7, which is received in a pocket 8 shown by dotted lines in Fig. 2, said pocket being formed in any suitable manner near the hinge or inner portion of the cover member 2.

The plate 7 and the hooks 6 are not only near the pad of receipts, but they hold in place a carbon sheet retainer shown best in Figs. 1 and 8. This retainer consists of a piece of sheet metal 11 folded upon itself at its upper edge as shown at 12, said upper edge forming a sort of hinge element. The end of the carbon sheet is received between

the folded portions of the retainer 11, and a clip 13 is used to firmly connect the free edge portions of the retainer, so as to clamp between the sides of the retainer the carbon sheet which is designated 14. The carbon sheet may be of any suitable kind commonly used, and may be renewed readily by taking the retainer 11 from the hooks 6, removing the clip 13, spreading the sides of the retainer 11 a little, inserting a carbon sheet, again applying the clip 13, and connecting the retainer with the hooks.

When inserting a fresh pad of receipts, the tab 5^a of the used pad is detached and 15 thrown away.

From the foregoing it will be apparent that I have devised a handy receipt book or holder by the use of which no liability of deception will arise in mishandling of receipts in one way or another, all of which is of importance in this particular art involving the accurate keeping of accounts.

Having thus described the invention what I claim as new is:

25 1. A device of the character described, including a cover member provided with oppositely opening pockets, a pad provided with a tab which is removably engaged by one of the pockets, a plate fitted removably

within the other pocket and provided with 30 outwardly projecting hooks arranged adjacent to the pad, and a carbon sheet retainer loosely engaged by the hooks and detachable therefrom.

2. A device of the character described, including a cover member, a pad thereon, hook members projecting outwardly from the cover member adjacent to the pad, and a carbon sheet retainer loosely engaged by the hooks and detachable therefrom, said 40 carbon sheet retainer comprising a piece of sheet metal which is folded on itself to provide a clamping body.

3. A receipt book or holder comprising cover members, one having a pocket thereon, a detachable plate received by said pocket and provided with hooks, a pad of receipts adjacent to said hooks, and a carbon sheet retainer engaged by the hooks and detachable therefrom.

4. An article as claimed in claim 3, in which the retainer comprises a piece of sheet metal folded on itself to provide a clamping body, and a clip to hold the body clamped on a carbon sheet.

50 55 In testimony whereof I affix my signature.

SAMUEL M. GREEN.
